UNITED STATES PATENT OFFICE.

KARL E. PEILER, OF HARTFORD, CONNECTICUT, ASSIGNOR TO HARTFORD-FAIRMONT COMPANY, OF CANAJOHARIE, NEW YORK, A CORPORATION OF NEW YORK.

METHOD AND MACHINE FOR FEEDING MOLten GLASS.

1,234,934.

Specification of Letters Patent. Patented July 31, 1917.

Application filed December 4, 1916. Serial No. 134,826.

To all whom it may concern:

Be it known that I, KARL E. PEILER, a citizen of the United States, residing at Hartford, in the county of Hartford and State of Connecticut, have invented new and useful Improvements in Methods and Machines for Feeding Molten Glass, of which the following is a specification.

This invention relates to the art of gathering separate masses of molten glass in suitable condition for subsequent shaping operations.

The object of the present invention is to provide a method and apparatus for feeding masses or gathers of molten glass, uniform in size, consistency and temperature, and in timed relation, to molds or other shaping devices.

In the embodiment of the invention illustrated herein this object is attained by flowing the viscous glass from the furnace outlet against a gathering head which is rotated to distribute the accumulating glass around the head. When the accumulation is sufficient for the purpose the head is slowed or stopped to permit the glass to shed downwardly by gravity and form a depending ball which is then severed and conducted away. These operations take place in a heated chamber in order to keep the glass in proper working condition and the gathering and severing implements are cooled so that they will best perform their functions.

The gathering head is mounted for axial movement toward and from the furnace outlet, to regulate the flow of glass to the head, and when desired, to arrest the flow more or less completely while a gather is being shed or discharged from the head.

In the views Figure 1 shows a side elevation of the active mechanisms and a section of the wall of the furnace and heating chamber. Fig. 2 is a section on the plane indicated by the dotted line 2-2 on Fig. 1 showing the front wall of the heating chamber. Fig. 3 is a section on the plane indicated by the dotted line 3-3 on Fig. 1 showing the adjustable means for periodically rotating the gathering head. Fig. 4 illustrates the distribution of the gather around the head.

The furnace 3 indicated in the views has a discharge outlet or spout 1, and an adjustable gate 2 for regulating the flow of glass to the outlet. The spout projects into a chamber 4 having walls of refractory mate-

rial. In the form shown the front wall is made of two sections 5 that are hung upon the upper edge of the top wall 6 so that they may be drawn apart and separated to permit access to the chamber and the withdrawal of the gathering head. Suitable gas burners 8 are arranged to blow gas flames through apertures 7 into the chamber.

The gathering head 9 of refractory material is attached to the end of a tubular shaft 10 that is provided with a pulley or friction roll 11. This shaft is mounted so that it will rotate in a sleeve 12 which is slidably held in a bearing 13 at the top of the frame 14. The gathering head shown is shaped like a turnip or an acorn, and is located in the hot chamber 4, with its apex and the axial line of the supporting shaft pointing toward and into the discharge spout 1. This head and its shaft are preferably tubular in order that air may be circulated through them to prevent the head from becoming overheated. For rotating the head at the proper time a pulley 11 on the shaft 10 is arranged to be engaged by the sectional driving disks 15. A portion of the periphery of each section of the driving disk is cut away or relieved, and these sections are adjustably secured together so that the relieved portion of the disk may be lengthened and shortened according to the time it is desired to arrest the rotations of the head. When the periphery of the disk engages the pulley the head is rotated, and when the relieved portion of the disk reaches the head it remains stationary.

The head 9 is adjusted longitudinally toward and from the spout by means of the nuts 16 which turn on threaded portions of the sleeve 12, and the bearing 13 has an extension 17 that projects into a cam groove in the cam 18. This cam groove is cut to give the desired longitudinal movement to the shaft and gathering head and it is mounted on the shaft 19 on which the sectional head rotating disk is mounted and which is provided with a driving gear 20.

As the molten glass flows through the discharge outlet from the furnace onto the head it is flared outwardly and distributed around the head, upon which a mass is thus accumulated. As this takes place the head is preferably retracted by the cam 18 from the outlet to facilitate and regulate the flow of glass. After a sufficient quantity has been gathered the rotation of the head

ceases and it is also preferably moved end-
wise, closer to the outlet, to diminish or
check further flow from the discharge out-
let. With the head nearly or quite sta-
5 tionary the glass sags or is shed from the
head and forms a depending ball, which is
then cut off by shear blades 21 and 24. The
lower blade 21 is fastened to a sleeve 22
which is provided with a bevel gear 23, and
10 the upper blade 24 is fastened to a shaft
25 that extends through the sleeve 22, and
is provided with a bevel gear 26. Engag-
ing these gears so the shears revolve op-
positely is a bevel gear 27 on a shaft 28
15 provided with a gear 29 in mesh with the
gear 20. This mechanism is timed so that
the rotating shear blades will come together
and cut off the depending mass of glass at
the proper time, allowing it to drop into
20 molds, either directly or through the chute
30, which is mounted below the heating
chamber on a stem or stud 32 that is ad-
justably held in a bracket 33 projecting from
the frame. A sprayer 34 connected with a
25 water supply is arranged to throw cooling
water upon the shears when they are turned
back away from under the furnace. A drip
pan 35 provided with a pipe 36 is located be-
neath the sprayer for collecting and conduct-
30 ing away the water which falls from the
sprayer.

The mechanism here shown may be driven
in any convenient way from, or in connec-
35 tion with, the glass shaping machine with
which it is associated, as for example by
means of a train of gears connecting with
the gear 29.

The supply of air for preventing the over-
heating of the gathering head may be ap-
40 plied in any well-known way. It is here
shown as being applied by means of a swiv-
eling air head or cap 38 mounted upon the
end of the hollow shaft 10, so that the lat-
ter may revolve within the air cap without
45 turning the latter. The air cap is provided
with pipe connections 39 and 40, the latter
of which is connected with a supply of air
under pressure, and is sufficiently flexible
50 to permit the longitudinal movements of
the gathering head. The air entering from
these pipes through the air cap 38 passes
longitudinally through the hollow shaft 12
to the gathering head and returns through
55 an interior pipe 41 in a manner well known
in this art.

The outlet for the glass is here shown to
be through a closed or tubular spout 1.
This, however, although preferable, is not
60 an essential feature, since the glass may un-
der some conditions or for some purposes
be discharged through an outlet open at
the top.

As the reciprocating head is moved away
from the outlet it tends to draw out and
65 thus facilitate the flow of the glass, besides

giving it more room to flow around the
head between the latter and the outlet. The
rotary movement of the glass as it is carried
by the head tends also to wipe or scour the
outlet, thus maintaining a free and clean
70 flow, and thereby tending to prevent accu-
mulations of chilled glass in and around
the outlet, assisted in this respect by the
drawing out action above referred to.

The viscous character of the glass makes
it usually unnecessary to move the head close
against the spout or outlet to stop or check
the flow of the glass to a sufficient extent.
The range or zone of longitudinal move-
80 ment may be adjusted by means of the nuts
16 while the machine is in operation, thus
establishing and maintaining under work-
ing conditions, the proper flow of the glass
and the extent to which the flow is arrested
when shedding the accumulated gather.
85

To facilitate the ready removal and re-
placing of the gathering head, a removable
cap or half-box 43 is provided for the bear-
ing 13, held in place by a bolt or bolts 44.
By removing these bolts and the cap 43,
90 and sliding back the front wall sections
5 and 5^a, the gathering head and its shaft
are free to be removed from working pos-
ition and another head substituted.

The size of the outlet and of the gather-
ing head, the degree of their inclination,
and other relevant features should be adapt-
ed to the character of the glass and the
95 size of the gathers to be formed. Similarly
understood in this art the various parts
should be adapted and adjusted to the per-
formance of their respective functions.

I claim as my invention:

1. The combination, with the discharge
105 outlet of a container for molten glass, of a
rotary gathering head located substantially
in axial alinement with the flow of glass
through said outlet, and means for rotating
said head.

2. The combination, with a container for
molten glass having a discharge spout, of
110 a rotary gathering head located in front of
and substantially in axial alinement with
said spout, and means for rotating said head.

3. The combination, with a container for
molten glass having an outlet spout, of a
115 rotary gathering head disposed in front of
and projecting into said spout, and means
for rotating said head.

4. The combination, with a rotary gather-
ing head, of a container for molten glass
having a flow outlet disposed adjacent to
the head and substantially in the axial line
120 of rotation thereof, and means for rotating
the head.

5. The combination, with the discharge
outlet of a glass furnace, of a rotary gather-
ing head disposed adjacent to the outlet, and
125 substantially in axial alinement therewith,

- means for rotating the head, and means for moving the head in an axial direction.
6. The combination with the discharge outlet of a glass furnace, of a rotary gathering head located with the axial line of its rotation pointing toward the outlet, means for rotating the gathering head, and means for adjusting the longitudinal position of the head.
- 10 7. The combination, with the discharge outlet of a glass furnace, of a rotary gathering head disposed in front of said outlet, means for rotating the head, means for reciprocating the head longitudinally, and means for adjusting the position of the longitudinal movements.
- 15 8. The combination, with a glass furnace having a discharge outlet, of a rotary gathering head located in front of said outlet, and means for variably rotating said head.
- 20 9. The combination, with a glass furnace having a discharge outlet, of a rotary and reciprocatory gathering head located in front of said outlet, mechanism for variably rotating said head, and mechanism for moving said head toward and from said outlet.
- 25 10. The combination, with a glass furnace having a discharge outlet, of a heating chamber about said outlet, a rotary gathering head located in said chamber in front of said outlet, and mechanism for variably rotating said head.
- 30 11. The combination, with a glass furnace having a discharge outlet, of a heating chamber about said outlet, a rotary and reciprocatory gathering head located in the chamber in front of said outlet, mechanism for variably rotating said head, and mechanism for moving said head toward and from said outlet.
- 35 12. The combination, with a glass furnace having a discharge outlet, of a rotary gathering head located in front of said outlet, mechanism for rotating said head, and a heating chamber inclosing said orifice and the gathering head, the front wall of said chamber being in separable sections to permit the withdrawal of the head.
- 40 13. A glass gathering apparatus consisting of a rotary and reciprocatory gathering head, rotary shear blades located below the head, mechanism for intermittently rotating the head, means for determining the periods of rotation of the head; mechanism for reciprocating the head, and mechanism for 55 rotating the shear blades.
- 45 14. The method of gathering charges of molten glass, which consists in flowing the glass, flaring the flowing glass outwardly and accumulating the flaring portion until 60 the desired size of gather is obtained.
- 50 15. The method of gathering charges of molten glass, which consists in flowing the glass, spreading and winding the glass in an outwardly flaring spiral form, until the 65 desired gather is obtained.
- 55 16. The method of gathering charges of molten glass, which consists in flowing the glass, spreading the flowing glass in an outwardly flaring form, and winding the flared 70 portion to accumulate the desired gather.
- 60 17. The method of gathering charges of molten glass, which consists in flowing the glass, spreading the glass as it flows in an outwardly flaring form, winding the flared 75 portion to accumulate the desired gather, and finally shedding the gather.
- 65 18. The method of gathering masses of molten glass, which consists in flowing the glass and assisting the flow by drawing action and at the same time winding the glass into 80 a mass, then checking the flow of glass and stopping the winding and allowing that glass which is wound to gather into a depending ball.
- 70 19. The method of gathering masses of molten glass, which consists in flowing the glass, assisting the flow by drawing action and at the same time winding the glass into 85 a mass, then checking the flow of glass and 90 stopping the winding and allowing the glass which is wound to gather into a depending ball and finally cutting off said depending ball.
- 75 20. The method of gathering masses of 95 molten glass, which consists in flowing the glass, assisting the flow by drawing action and at the same time winding the glass into a mass in a heated atmosphere, then checking the flow of glass and stopping the winding and allowing that glass which is wound to gather into a depending ball and finally cutting off said depending ball.
- 80 Signed at Hartford, Conn. this 1st day of December, 1916.
- KARL E. PEILER.
